UNITED STATES PATENT OFFICE.

JOHN HARLEMAN, OF KANSAS CITY, MISSOURI, ASSIGNOR TO AETNA LIGHT AND HEAT COMPANY, A CORPORATION OF MISSOURI.

GENERATOR.

No. 903,856.

Specification of Letters Patent.

Patented Nov. 17, 1908.

Application filed August 12, 1907. Serial No. 388,138.

To all whom it may concern:

Be it known that I, JOHN HARLEMAN, a citizen of the United States, residing at Kansas City, in the county of Jackson and State of Missouri, have invented certain new and useful Improvements in Generators; and I do declare the following to be a full, clear, and exact description of the invention, such as will enable others skilled in the art to 10 which it appertains to make and use the same, reference being had to the accompanying drawings, and to the letters and figures of reference marked thereon, which form a part of this specification.

15 My invention relates to generators, and more particularly to a device of that class in which vapor is generated from a liquid fuel and treated to secure a combustible gas for lighting or heating purposes.

20 The principal object of my invention is to provide a generator for heating or lighting systems, which is provided with a return pipe and burner for heating the liquid fuel entering the generator, and a further object 25 is to provide a generator which is simple and economical, both in construction and operation.

In accomplishing these objects I provide the improved details of structure which will 30 presently be fully described and pointed out in the claim, reference being had to the accompanying drawings forming part of this specification, in which like reference numerals refer to like parts throughout the several views, and in which:—

Figure I is a view in side elevation, of a 35 generator constructed according to my invention. Fig. II is an enlarged sectional view of a portion of the generator tube. Fig. III is a central vertical sectional view 40 of Fig. I.

Referring more in detail to the parts:—1 designates the main fuel feed pipe, which 45 may be mounted on a base 2, or other suitable means, and projects at its upper end through the generator casing 3, where it is threaded into, or connected in a suitable manner with a generating tube 4 contained in said casing.

50 Tube 4 has a central channel 5, provided with a branch 6, which latter registers with the feed channel 7 in pipe 1; said pipe having a port 8 through which the fuel is delivered to the apparatus.

In the channel in pipe 4 is a valve stem 55 10, provided at its inner end with a wire 11, which is adapted to project through the contracted exit port 12 of said tube, and has a flange 13 adapted to seat against the shoulder 14 in channel 5 between the connecting 60 channel 6 and port 12, to close the channel against the passage of fuel therethrough.

Channel 5 is not of the same diameter throughout, but tapers inwardly from near the exit port to the seat of flange 13, and has 65 a beveled head 23 leading to port 12, to assist the valve needle in finding its seat therein.

Stem 10 is threaded to tube 4 at 18, and projects through a stuffing box 15 which is carried on the outer end of said tube by a 70 cap 16. At its outer end stem 10 is provided with the handle 17, by which it is operated, as will presently be described.

Tube 4 is offset inwardly at its inner end, and projects through the end of casing 3, 75 with its shoulder bearing against the inner surface of said casing, and carried on the projecting portion of said tube is a mixing chamber 19, having air inlet ports 20, and a series of perforations 21 between said ports 80 and casing 3.

Telescoping within the free end of the mixing chamber is a tube 22, and 22' indicates a set screw for securing said tube in a desired position in relation to the air inlet 85 ports; the outer end of said tube also telescoping within the tube 24 which leads to the lamps or other burners which the vapor from the generator is to supply with fuel.

25 indicates a union, of any suitable pattern, with which pipe 24 is connected, and from which individual supply pipes may lead to separate lamps or burners. Opening from union 25 is a pipe 26, which leads back to the casing 3, and projects thereinto beneath the main tube 4, there being perforations in said pipe to form a burner 27, through which vapor may escape and be burned beneath tube 4, for the purpose of heating same.

28 indicates a mass of absorbent, and preferably non-inflammable material which is packed around pipe 26, and which may be saturated with liquid fuel when it is desired to start the generator, to create an initiatory 105 heat for generating the first flow of fuel.

When in use the parts are assembled as described, and the vapor tube branched to

any desired number of lamps, or to other vapor burning devices, and the port 8 connected with a source of liquid fuel supply.

When an operation of the generator is desired, a small quantity of oil or gasolene is poured over the absorbent material in the bottom of casing 3, and the liquid fuel turned into the tube 4 by withdrawing the flange 13 from its seat, to allow the liquid to flow into the portion of the tube channel over the saturated packing in the bottom of the casing. The oil or gasolene carried by the packing is then ignited and the heat rising therefrom heats the tube 4, and vaporizes the liquid in the tube channel. After vaporization, the fuel passes through the exit port 12, into and through the mixer to the supply pipe 22, the flow being regulated by the valve 11 on the end of stem 10. As the vapor passes through the mixer, it mixes with the air admitted through ports 20 and perforations 21, to form a combustible fuel gas, a suction being formed in the direction of the supply pipe, which tends to draw the air into the mixer and force same through said pipe. As before stated, pipe 22 is supplied with a suitable union for branch pipes, or carries said branches directly, one of said branches being the return pipe 26, which conducts the vapor back to the burner 27, beneath the generating tube, so that after the initiatory generation, the burner may be lighted, and the liquid flowing into the tube 4 be vaporized thereby to supply the various burners with proper fuel. After the burner 27 has been lighted, the fuel mixture may be regulated by moving the telescoping member 22 to increase or diminish the quantity of air admitted through ports 20, so that a perfect mixture may be secured. By constructing the channel in the generating tube in the manner described, sufficient space is provided for the expansion

of the gas after generation, so that the pressure therefrom does not interfere with the proper regulation of the inlet valve nor the inflow of liquid.

I have shown an improved valve in connection with my generator, which prevents the widening of the port 12, incident to the usual jamming by the needle valve commonly used in apparatus of this kind, which valve consists of a needle of nickel steel, or like material, and is of the same diameter throughout, and rounded at the end, so that when moved toward its port, it will readily find the entrance, or if it should not register perfectly will bend instead of jamming and enlarging the port, and when seated entirely within the port will not fill same completely and grind the surface when turned, so as to prevent a proper regulation of the fuel.

Having thus described my invention, what I claim as new therein, and desire to secure by Letters Patent is:—

The combination with a generator mechanism, of a mixer having a single chamber, said chamber being provided, near one end, with main air intake ports, and near its opposite end with auxiliary air intake ports of less area than said main ports, a discharge member leading from said generator mechanism and adapted for discharge into the mixer chamber intermediate the main and auxiliary air intake ports, a fuel supply pipe, and a connecting tube adapted to slide in both said mixing chamber and supply pipe substantially as and for the purpose set forth.

In testimony whereof I affix my signature in presence of two witnesses.

JOHN HARLEMAN.
